UNITED STATES PATENT OFFICE.

ARNOLD ZUKOR, OF NEW YORK, N. Y.

AUTOMATIC STOP FOR RAILWAYS.

1,106,910.

Specification of Letters Patent. Patented Aug. 11, 1914.

Application filed March 10, 1914. Serial No. 822,703.

To all whom it may concern:

Be it known that I, ARNOLD ZUKOR, a citizen of the United States, and resident of the city of New York, in the county of New York and State of New York, have invented certain new and useful Improvements in Automatic Stops for Railways, of which the following is a specification.

The present invention relates to improvements in automatic stops for railways, and is more particularly adapted for use in connection with railway tracks which are divided into short sections or blocks by signaling means, although, as will hereinafter appear, it may be used in connection with switches also.

One of the objects of the invention is to provide a simple and efficient device of the type mentioned, by means of which a train may be brought to stop automatically should it run past a signal, or should a switch in advance of the train be open.

With these and other objects in view, which will more fully appear as the nature of the invention is better understood, the same consists in the combination, arrangement and construction of parts hereinafter fully described, pointed out in the appended claims and illustrated in the accompanying drawings, it being understood that many changes may be made in the size and proportion of the several parts and details of construction within the scope of the appended claim without departing from the spirit or sacrificing any of the advantages of the invention.

One of the many possible embodiments of the invention is illustrated in the accompanying drawings, in which:—

Figure 1 is a side elevation of a portion of a locomotive with the invention applied thereto, and Fig. 2 is a diagrammatic rear elevation of said locomotive with the stopping device carried thereby.

In the drawings, the numeral 10 indicates a railroad track, on which the trains run in the direction indicated by the arrow shown in Fig. 1 of the drawings. This track is divided for signaling purposes into sections or blocks. The division into blocks is accomplished by placing at predetermined intervals, preferably equidistantly, along the track signaling devices, each of which includes a vertical bar 11, which extends a substantial distance above the level of the ground, and carries an inwardly ex-

tending horizontal projection 12. These bars may be set either by hand, as clearly described in U. S. Letters Patent No. 1,053,691, granted to me Feb. 18, 1913 for railway signals, or the said bars may be set automatically by a train, as disclosed in my pending application for U. S. Letters Patent, Ser. No. 805,345, filed Dec. 8, 1913, and entitled automatic railway signals. Normally, that is to say when the track is clear, these bars are in their lower positions; if, however, a train is preceded by a train that runs in the block or section ahead, these bars are in their elevated positions shown in Figs. 1 and 2 of the drawings.

The locomotive of a train is indicated in the drawings by the numeral 13. To one side of the cab portion 14 of this locomotive is pivoted at 15 a two-armed lever 16, the lower free end of which is adapted to bear against the bars 11, when the latter are raised as above described. The upper end of the lever 16 is provided with a gear segment 17, meshing with a pinion 18, that is fixedly attached to a spindle 19, the latter being journaled in bearings 20. Stops 21 limit the movement of the lever. The spindle 19 extends into the cab and has keyed, or otherwise attached thereto, a second pinion, denoted by the numeral 22, meshing with a toothed rack 23, that is slidably disposed in guides 24. The lower end of this rack is adapted to bear against an extension 25 of the starting lever 26 of the locomotive, said starting lever controlling the admission of steam into the cylinders of the engine of the locomotive. The lever 16 is adapted to contact with a lug 27 upon the stem 28 of a valve 29 of the air brake mechanism of the locomotive.

The operation of this device is as follows: Normally the lever 16 is disposed substantially vertically upon the locomotive, as clearly shown in Fig. 1 of the drawings, in which case one end of the gear segment 17 bears against one of the stops 21. The rack 23 is then in its upper position (Figs. 1 and 2). When the train is running at normal speed, its starting lever 26 is disposed in a plane at an angle to the vertical plane (Fig. 2), and in this case the extension 25 bears against the lower end of the rack 23. Let us suppose that the signal bar 11 has been raised into the position shown in Figs. 1 and 2 of the drawings, in which position its projection 12 is in the

path of the lower end of the lever 16, that is to say in a position which is to indicate to the engineer of the train that the track is not clear. As the locomotive runs past 5 the signal bar 11, the lever 16 is swung in a manner that its upper end moves in the direction of the arc-shaped arrow shown in Fig. 1 of the drawings, whereby the pinion 18 is turned in a corresponding direction, 10 thereby resulting in a lowering of the toothed rack 23, thus bringing the starting lever into a substantially vertical plane, thereby shutting off the steam from the cylinders of the engine. At the same time the 15 lever 16 acts upon the stem 28 of the air valve 29, causing the air brakes to be applied and bringing the locomotive to stop. The engineer of the train, upon receiving a signal to proceed, shifts the starting lever 20 26 into the position shown in Fig. 2 of the drawings, thereby raising the toothed rack 23, which will result in bringing the lever 16 into normal position, shown in Fig. 1 of the drawings.

25 It is obvious that the signal bar 11 may be connected with a switch in advance thereof in a manner that, whenever the switch is in its open position, the lever is in its raised position, and, whenever the 30 switch is shifted to its closed position, the said lever is in its lower position. Obvi-

ously, thus any train would be stopped when a switch is open before the switch is reached by the train.

What I claim is:—

In an automatic railway stop, the combination with a two-armed lever pivoted to the side of a locomotive provided upon its upper end with a gear segment, its lower end being adapted to coöperate with a signal bar disposed upon the side of the track, of a starting lever controlling the admission of steam into the locomotive, a spindle rotatably mounted upon the locomotive, a pinion carried by said spindle in mesh with 40 said gear segment, a toothed rack adapted to bear against said starting lever, a second pinion upon said spindle meshing with said rack, whereby when said two-armed lever is shifted by said signaling bar said starting lever is set to closing position, and when said starting lever is moved to opening position said two-armed lever is returned to its normal position.

Signed at New York, in the county of New York and State of New York, this 9th day of March, A. D. 1914.

ARNOLD ZUKOR.
